(57) **CLAIM**

The ornamental design for a hygienic toilet seat and lid combination unit, as shown and described.

DESCRIPTION

FIG. 1 is a perspective view from above of the hygienic toilet seat and lid combination unit of this invention.

FIG. 2 is a perspective view from the underside of the hygienic toilet seat and lid combination unit shown in FIG. 1.

FIG. 3 is a front elevational view of the hygienic toilet seat and lid combination unit shown in FIG. 1.

FIG. 4 is a top plan view of the hygienic toilet seat and lid combination unit shown in FIG. 1.

FIG. 5 is a bottom plan view of the hygienic toilet seat and lid combination unit shown in FIG. 1; and,

FIG. 6 is a side elevational view of the hygienic toilet seat and lid combination unit shown in FIG. 1.

The view from the opposite side from that side shown in FIG. 6, is a mirror image thereof.
